Filed Sept. 1, 1972, Ser. No. 285,604

Term of patent 14 years

Int. Cl. D17—01

U.S. Cl. D56—9

FIG. 1

FIG. 2FIG. 3

FIG. 1 is a front, top and left side, perspective view of a piano showing our new design;

FIG. 2 is a front elevational view; and

FIG. 3 is a right side elevational view.

The back of the piano is conventional. Each of the ornamental designs in the upper front board, partially obscured by the music desk, is symmetrical. The upper front board is otherwise plain and unornamented.

We claim:

The ornamental design for a piano, substantially as shown and described.
